(57) **CLAIM**

The ornamental design for an ventilation garment, as shown and described.

DESCRIPTION

FIG. 1 shows a perspective view of the invention;

FIG. 2 shows a front view of the invention;

FIG. 3 shows a back view of the invention;

FIG. 4 shows a right side view of the invention;

FIG. 5 shows a left side view of the invention;

FIG. 6 shows a top view of the invention; and,

FIG. 7 shows a bottom view of the invention.

The broken lines shown in the drawings show unclaimed subject matter only and form no part of the claimed design.
